UNITED STATES PATENT OFFICE.

FRANZ PUENING, OF ASPINWALL, PENNSYLVANIA.

HEATING METHOD AND APPARATUS.

Application filed January 31, 1923. Serial No. 616,138.

To all whom it may concern:

Be it known that I, FRANZ PUENING, a citizen of the United States, and resident of Aspinwall, in the county of Allegheny and 5 State of Pennsylvania, have invented a new and useful Improvement in Heating Methods and Apparatus; and I do hereby declare the following to be a full, clear, and exact description thereof.

10 My invention relates to the art of heating furnaces, chambers, retorts, leers, and any other objects or spaces where it is necessary that the heat be closely regulated, maintained uniform, and kept below the temperature 15 of combustion of ordinary fuel.

More specifically, my invention relates to a system of heating wherein hot gases are reciprocated rapidly in contact with the object or space to be heated, and are given 20 additional heat during each reciprocation either by introducing fresh gases of combustion into the reciprocating body of gases or by passing the reciprocating gases in contact with a source of heat.

25 One object of my invention is to provide a system of heating by means of reciprocating gases in which a single source of heat shall be arranged to supply equal amounts of heat to a heating chamber alternately from 30 two sides of said chamber.

Another object of my invention is to add heat to the reciprocated gases at each reciprocation while they are moving away from the object or space to be heated and to 35 thoroughly distribute the new heat in the gases before reciprocating them again through the heating chamber.

In my copending applications for Letters 40 Patent filed July 16, 1920, Serial No. 396-693, December 11, 1922, Serial No. 606,037, and January 18, 1923, Serial No. 613,396, I have disclosed several methods of carrying out the reciprocating-gas system of heating.

45 In all of these prior methods two sources of heat were provided, one burner or set of burners being located on each side of the body or space to be heated. If the two burners or sets of burners are of exactly equal heat intensity, an equal amount of heat is transmitted from each side to the space or object to be heated. In practice it requires continuous attention to maintain two sets of burners or other heat sources at exactly the same heat intensity, and any variation in this respect produces corresponding variations in the heat delivered by

the reciprocating gases. It has also to be recognized that the investment for two sources of heat is higher than for only one, and that the heat radiation losses from two 60 high-temperature sources of heat are greater than from only one.

In my prior systems, where the reciprocating gases are heated at two points in their reciprocation, it is of course possible 65 to extinguish one of the burners or sets of burners and to heat the reciprocating gases at one point only in their reciprocation. It is evident, however, that in such a case the heat becomes less intense on the side of the 70 heating chamber where the heat source was extinguished, and that the heat within the heating chamber is no longer uniform.

According to my present invention I provide 75 a system of heating by means of reciprocating gases, wherein equal amounts of heat are supplied to the heating chamber alternately from two sides, but with the use of only a single source of heat. For this purpose I provide a by-pass to the heating chamber or the heating flues in such a manner that the reciprocated gases are divided 80 into two streams during each reciprocation. The dimensions of the by-pass are preferably such that only the smaller portion of 85 the total reciprocating gas volume can pass through it, while the bulk of the gas passes through the heating chamber proper. The reciprocation of the gases is produced as in my prior applications by means of a piston member which may be arranged to reciprocate in a straight line, to oscillate about a fixed pivot, or in any other manner as may be desired.

The motion of the piston in one direction 95 creates a pressure in the space toward which it moves and a suction in the space from which it moves away. This pressure and this suction extend in both directions in an ever diminishing intensity until they meet 100 at a certain point of the heating chamber and also at a point of the by-pass, where pressure as well as suction have disappeared and neutral conditions exist. At this neutral point in the by-pass the additional heat 105 is introduced and added to the smaller stream of gases which reciprocate through the by-pass.

This by-pass conducts the gases into the 110 chamber containing the piston which reciprocates the gases through the system, and the hot gases from the by-pass are therein

thoroughly mixed with the older gases which have already reciprocated through the system and have given up a portion of their heat. In this way the gases are mixed uniformly before being introduced into the heating chamber.

Another important feature of my invention is that heat is not added to the reciprocated gases while they are on their way toward the body to be heated, but while they are moving away from it into the auxiliary chamber in which the piston reciprocates. There they are thoroughly mixed with the older gases coming from the body to be heated with the result that the temperature of the mixed gases, when they are returned to the bodies to be heated, is even more uniform than in the systems shown in my prior applications. This is of importance where the bodies to be heated are very sensitive to overheating. Other advantages of my invention will appear from the following description, taken in connection with the accompanying drawing, wherein Fig. 1 is a longitudinal vertical sectional view taken centrally through a furnace having an oscillating piston for reciprocating heating gases in the furnace chamber; Fig. 2 is a transverse vertical sectional view taken substantially on the line 2—2, Fig. 1; Fig. 3 is an enlarged side view, partly in elevation and partly in section, of a portion of the oscillating piston shown in Figs. 1 and 2; Fig. 4 is an end elevational view of the piston construction shown in Fig. 3; Fig. 5 is an enlarged end elevational view of a portion of the furnace construction of Figs. 1 and 2; Fig. 6 is a horizontal sectional view through a furnace provided with a vertically moving piston for reciprocating gases through the furnace chamber; and Fig. 7 is a vertical sectional view taken substantially on the line 7—7, Fig. 6.

It is to be understood that my invention is in no way limited to the heating of any particular object or class of objects, and that the structures shown in the accompanying drawing are intended merely to illustrate some of the many embodiments of which my invention is capable.

Figs. 1 to 5 show the principles of my invention as applied to an elongated furnace chamber 2 through which hot gases are reciprocated transversely by means of an oscillating piston 3. The piston 3 is enclosed within a piston chamber 4, the lower wall 5 of which is circularly curved about the axis of rotation of the piston 3. A hollow shaft 6 supports and swings the piston 3 and is mounted upon bearings 7 resting upon standards which are located outside of the piston chamber, and which consist of horizontal beams 8 and vertical supports 9. A crank 10 is shown attached to one end of the hollow shaft 6 and may

be connected to any suitable mechanism for oscillating the shaft 6, such mechanism being shown, for example, in my prior application for Letters Patent, Serial No. 613,396.

Figs. 3 and 4 show one suitable method of constructing the oscillating piston 3 so as to be light, strong and capable of being cooled by means of water or other cooling medium. As shown in these figures, the hollow shaft 6 is provided at intervals with tapped openings in which are received pipes 11, the upper ends of which extend through the openings in the shaft 6 and have their upper ends closed by means of plugs 12. The lower ends of the pipes 11 are attached to and communicate with a horizontal pipe 13, and each pipe 11 has near its upper end one or more lateral openings 14 communicating with the interior of the hollow shaft 6. The flow of liquid through the shaft 6 is controlled by means of partitions 15 having restricted openings 16. One end of the shaft 6 is connected to a suitable source of water or other cooling fluid, and this fluid traverses the pipes 11 and 13, as well as the shaft 6, thus effectively cooling the piston.

The panels in the frame which is formed by the shaft 6 and the pipes 11 and 13, are covered with plates 17 which may be plain rectangular metal sheets or may, with advantage, be corrugated, as shown on the drawing. These plates may be secured in place by means of bolts 18 which extend through the plates near their upper and lower edges, and also extend through openings in webs or ribs 19 which are welded or otherwise secured to the shaft 6 and to the pipe 13.

The oscillating piston may extend the full length of the furnace or, in a long furnace, may be divided into two or more sections. Fig. 1 shows such a construction in which the piston consists of two sections of equal length separated by a vertical wall 20 which also may provide an intermediate bearing for the hollow shaft 6. This vertical wall also controls the fresh hot gases which are introduced into the system in the manner described below, and compels these fresh gases to reciprocate through the heating chamber 2 before reaching the rear portion of the piston chamber 4.

In order to prevent gases from passing above the shaft 6, a sealing member 21 extends the full length of the piston chamber 4 and rests loosely upon the upper surface of the shaft 6, being held in position by means of hooked brackets 22 which are secured to the underside of an arch 23. The sealing member 21, like the piston 3, may be constructed in one or more sections, as may be found convenient.

The piston chamber 4 and the main heating chamber 2 are connected by means of

vertical flues 24, the lower ends of which open into the piston chamber 4, while their upper ends open into spaces 25 which extend the full length of the furnace and are separated from the main heating chamber 2 by vertical walls 26 having openings 27 for the passage of hot gases, the effective size and number of these openings being made variable, if desired, by means of pieces of brick shown at 28.

The piston chamber 4 is separated from the main heating chamber 2 by the arch 23 and by an additional arch 29 which is of sufficient depth to contain a horizontal flue 30 through which fresh hot gases are added to the gases which are reciprocated at each stroke of the piston 3. The flue 30 preferably extends beneath only a portion of the length of the heating chamber 2 for reasons which will be discussed below, although this flue may, if desired, be made to extend the full length of the heating chamber 2. At its outer end the flue 30 communicates with a fire-box 31 into which projects a burner 32.

In the bottom of the flue 30 and midway between its sides, are a row of openings 33 that are connected by means of curved by-pass channels 34 with the vertical flues 24 which are adjacent to the flue 30. In order to adjust the effective size of the openings 33, bricks 35 are provided to rest on the bottom of the flue 30 and may be adjusted to close the openings 33 to any desired extent by means of a rake or other suitable implement inserted through an opening 36 in the front wall of the fire-box 31.

The furnace and its attachments are so constructed as to be capable of being taken apart for shipping or storing. For this purpose I dispense with ordinary brick or concrete foundations and mount the furnace upon a structural steel foundation frame, including transverse horizontal channels 37, vertical channels 38, and inclined struts 39 which are bolted at their lower ends to the transverse channels 37 and are secured at their upper ends to the vertical channels 38 by means of gusset plates 39^a. As best shown in Fig. 5, longitudinal channel beams 40 are secured to the upper ends of the vertical channels 38 by means of angle pieces 40^a and other longitudinal channel beams 41 are bolted to the upper flanges of the channel beams 40. The channel beams 41 open toward each other and are inclined to form skewback seats for the ends of the arch 23 which supports the weight of the furnace walls and roof. Horizontal angles 42 are secured to the channels 37 and 38 for adding rigidity to the framework. A curved metal shell 43 is attached at its upper edges to the lower flanges of the channels 41 and serves to support the curved wall 5 of the piston chamber 4.

As in all my reciprocating-gas systems of

heating where fresh hot gases are added to the reciprocated gas body, it is necessary to withdraw waste gases from the present system corresponding in volume to the fresh hot gases that are added to the system. For this purpose I provide an outlet 45 at the rear end of the furnace, this outlet being preferably located at the floor of the furnace, and midway between its sides. As shown on Fig. 2 the outlet 45 communicates through a pipe 46 with a pipe 47 which conducts the waste gases to a suitable chimney or which may itself act as a chimney.

In the operation of the furnace shown in Figs. 1 to 6, the piston 3 oscillates within the chamber 4 and at each stroke drives hot gases ahead of it. The courses followed by these gases are indicated by means of arrows on Fig. 2, it being assumed that the piston 3 at this moment is moving to the left in Fig. 2. The greater portion of the gases forced ahead of the piston pass up through the flues 24 at the left, enter the heating chamber 2 through the openings 27, and return to the piston chamber through the vertical flues 24 at the right. Another and smaller portion of the moving gases enters the by-pass channels 34 and again joins the main stream of gases in the vertical flues 24 at the right of Fig. 2. Hot gases from the burner 32 are added to the gases which traverse the by-pass channels 34, and these fresh gases are added to the main body of the reciprocating gases while the gases are moving toward the piston chamber 4. While the space at the right of the piston in Fig. 2 is being filled, the fresh hot gases which have been brought in through the by-pass channels are thoroughly mixed with the older gases from the main heating chamber 2. When the movement of the piston 3 is reversed, the same action takes place in the reverse direction, the gases that are now forced up through the flues 24 at the right of Fig. 2 being very uniform in temperature on account of the mixing action just mentioned.

It is to be noted particularly that the openings 33, through which fresh hot gases are added to the reciprocating gases, are located at a point of neutral pressure, that is to say, where there is neither pressure which would interfere with the issuance of hot gases through the openings 33, nor substantial suction which would draw gases through these openings at an unduly high rate. This condition is shown numerically on Fig. 2, it being assumed that the piston 3 is moving to the left in this figure and is developing a pressure of one unit. Immediately in front of the piston 3 there is a positive pressure of +1 unit, and immediately behind it there is a negative pressure or suction of -1 unit. In those parts of the by-pass channels 34, where the gases

enter these channels, there is an intermediate positive pressure which is indicated on the drawing as $+1/2$ of the original 1 unit, and in the opposite portions of the 5 by-pass channels 34 there is a negative pressure or suction which is indicated as $-1/2$ of the original 1 unit. At the point where the openings 33 communicate with the by-pass channels 34, the positive and negative 10 pressures exactly balance each other, so that there is neither pressure nor suction at this point. This condition of neutral pressure, indicated by the symbol ± 0 , exists throughout the stroke of the piston, 15 and when the direction of the piston is reversed the neutral condition is maintained, although the pressures and suctions are reversed in the system.

Similarly, the outlet 45 through which 20 waste gases are withdrawn from the furnace is located at a point of neutral pressure indicated by ± 0 , this neutral condition being produced, as in the by-pass channels 34, by the balancing of the positive and negative pressures produced by the piston 25 3.

The portion of the heating chamber 2 which is adjacent to the horizontal flue 30 is maintained at a higher temperature than the remainder of the heating chamber, for the reason that the hot gases supplied through this flue and through the by-pass flues 34 must reciprocate several times through the heating chamber 2 and the piston chamber 4 before reaching the opposite end of the heating chamber, and receive no additional heat beyond the end of the flue 30. The temperature flow is also retarded by the partition 20 in the piston chamber. A progressively decreasing temperature is thus produced in the heating chamber, this condition being desirable when the articles to be heated are moved through the heating chamber from the cooler end to the hotter end, as in a tunnel kiln. A similar arrangement may be employed in heating vertical tanks or the like, the more intense heat being applied to the upper end of the tank and the cooler waste gases being withdrawn from the lower end of the tank. In such a case, the flues for the gases may be arranged as they would be in Fig. 1 if the construction of Fig. 1 were turned on end with the fire-box above and the outlet for waste gases below.

60 This arrangement of flues for heating elongated objects or spaces may be varied by making the flue 30 extend the full length of the heating chamber 2. Another variation which may be made in the construction of Figs. 1 to 5 consists in placing the flue 30 and the fire-box 31 below the piston chamber 4 instead of between the piston chamber and the main heating chamber, in which case the fresh hot gases may be in-

troduced into one or both ends of the flue 30 or at one or more intermediate points; or the flue 30 may be placed above the heating chamber 2.

The body of hot gases which reciprocates in the system of Figs. 1 and 2 may be considered as a stream having its edges at the front and rear of the furnace and flowing transversely to the long axis of the furnace. It will be seen that the fresh hot gases are added to this stream at or near one of its edges and that the waste gases are withdrawn from the flowing stream at or near its opposite edge. 70 75

Figs. 6 and 7 of the drawing show a furnace chamber 52 enclosed by walls 53 of refractory material and having near its ends vertical walls 54 which separate the main furnace chamber 52 from smaller end chambers 55. The walls 54 are provided with openings 56 through which heating gases are admitted to the chamber 2, and which serve to distribute the heating gases uniformly throughout the cross-section of the heating chamber. 80 85 90

The furnace chamber 52 may contain any sort of objects to be heated. By way of illustration, I have shown an arrangement for heating liquid, consisting of vertical tubes 57 communicating at their upper and lower ends with headers 58 through which the liquid to be heated is brought to and removed from the tubes 57 by any suitable circulating means, not shown. 95

For the purpose of reciprocating hot gases through the furnace chamber 52, I provide a piston 60 reciprocating vertically in a chamber 61 formed by circularly curved walls 62. The piston 60 and its attachments may be similar in construction to those described and claimed in my copending application for Letters Patent filed December 11, 1922, Serial No. 606,037. As best shown on Fig. 7 the piston consists of two curved discs 63 of metal with a ring 63^a between them. These discs may be covered by heat-insulating material, as shown at 64. The piston is suspended from a hollow rod 64^a which extends through an opening 65 in the top of the piston chamber and through a gland 66. The space within the piston is divided into two chambers by means of a horizontal plate 67 having openings 68 near its outer edge. Cooling fluid is supplied to the piston through a tube 69, the lower end of which communicates through an opening 70 in the horizontal plate 67 with the lower chamber of the piston, and which is connected at its upper end by means of a coupling 71 to a source of water or other cooling medium. The cooling fluid passes from the lower chamber of the piston into the upper chamber through the openings 68, and thence passes upwardly through the space 72 between the 130

- tube 69 and the inner wall of the piston rod 64^a. A coupling 73 is attached to the upper end of the piston rod 64^a for conveying the cooling fluid away from the piston.
- 5 The piston and its cooling attachments just described are pivotally suspended from a link 75 which is itself pivotally suspended from the outer end of a rocking lever 76 that is mounted on a fixed pivot 77 and is connected by means of a link 78 to a crank 79 on a shaft 80. The shaft 80 is mounted in a bearing 81 and is driven, through a set of reduction gearing 82 and a suitable coupling 83, from an electric motor 84.
- 10 The piston chamber 61 communicates with the furnace chamber through upper and lower flues indicated at 85 and 86, respectively. The lower surface 87 of the flue 85 slopes downwardly and communicates with a lateral flue 88, the lower surface of which also slopes downwardly to the line 89 where it joins the floor of the furnace chamber. Similarly, the upper surface 90 of the lower flue 86 slopes upwardly and communicates with a lateral flue 91, the upper surface of which also slopes upwardly to the roof of the furnace chamber. By this arrangement of flues, the hot gases from the piston chamber are distributed in substantially 25 equal amounts over the cross section of the furnace chamber, this distribution being made still more uniform by the perforated walls 54 with the openings 56, as described above.
- 30 Heat is supplied to the piston chamber shown in Figs. 6 and 7 from a single source of heat represented by a burner 95 which discharges its flame into a fire-box 96 communicating through a port 97 with a vertical by-pass flue 98 which communicates with the upper and lower ends of the piston chamber 61 through ports 99 and 100, respectively.
- 35 Since fresh hot gases are continuously supplied to the system from the burner 95, it is necessary to withdraw continuously corresponding volumes of waste gases. For this purpose an outlet port 101 is provided in the lower part of the heating chamber 52 midway between its ends and on the side of the heating chamber away from the piston. The outlet port 101 is connected by means of a vertically elongated pipe 102 with a chimney 103. Since the outlet port 101 is located at the center of the heating chamber the gases discharged through it have given up the greater part of their available heat, because they have been in contact with one-half of the objects to be heated. The release of waste gases at this central point is preferred in case the temperature of the circulated and released gases is relatively low. If this temperature is higher it would be preferable to release the gases only after they have passed over all the bodies to be heated
- 40 and release them alternately at the openings 104 and 105, as described in my previous applications. In order to provide for thus withdrawing waste gases from the ends of the heating chamber, pipes 106 and 107 may connect the openings 104 and 105 with the chimney 103. Dampers 108 and 109 are provided in the pipes 106 and 107, respectively, and are connected to open and close alternately in time with the reverse movements of the piston 60, so as to discharge waste gases through the opening 104 while heating gases are entering at the right end of the chamber 52, Fig. 6, and to discharge the waste gases through the opening 105 while heating gases are entering at the left end of the heating chamber. Mechanism for operating such dampers is shown in my prior application, Serial No. 606,037, filed December 11, 1922.
- 45 When the piston 60 moves upwardly it forces hot gases through the flues 85 and 88 into the chamber 55, at the left of Fig. 6, and thence through the openings 56 into the heating chamber 52. A similar volume of gases is drawn out of the right end of the heating chamber and through the flues 91 and 86 into the piston chamber 61 below the piston 60. At the same time a portion of the gases above the piston moves through the by-pass flue 98 into the space below the piston. Fresh hot gases from the fire-box 96 are supplied into the by-pass flue 98 and enter the space below the piston 60 along with the gases traversing the by-pass flue. These mixed gases, on issuing into the piston chamber through the port 100, mingle with the gases which enter the piston chamber through the flue 86. When the piston 60 descends the same operation takes place in the reverse direction, the main body of hot gases being forced into the right end of the heating chamber through the flues 86 and 91, and a similar volume of gases returning to the piston chamber through the flues 88 and 85, where they mingle with fresh hot gases supplied from the fire-box 96.
- 50 During these reciprocations of the piston, the surplus gases are continuously discharged from the piston through the outlet port 101, the pipe 102 and the chimney 103, or alternately through the outlets 104 and 105 as described above.
- 55 Two or more heating chambers such as the heating chamber 52 of Figs. 6 and 7, may readily be grouped around a single piston, such as the piston 60, and may be connected to the piston chamber by suitable flues for simultaneous heating. This arrangement is desirable when the heating chambers are comparatively small, as in certain types of retorts.
- 60 It will be observed that in the system shown in Figs. 6 and 7, as in the system of Figs. 1 to 5, fresh hot gases are introduced

85

into the reciprocating gases at a point where the gas pressure is neutral and waste gases are withdrawn at similar points where the gas pressure is again neutral.

5 The systems shown above, wherein a single heat source is employed to bring heat from two directions into a heating chamber, has two main advantages. Since only one heat source is required, the construction and 10 operation of the system is greatly simplified and the expense of construction is reduced. An important feature incident to this advantage is that the temperature of the hot gases moved alternately from opposite 15 sides to the objects to be heated is absolutely uniform, since the same source of heat supplies equal heat to each side of the heating chamber.

20 The second main advantage of my present system is that the temperature of the hot gases thrown from two sides against the bodies to be heated is thoroughly homogeneous, because no portion of the new heat supplied at each reciprocation is added to 25 the reciprocating gases while they are on their way toward the bodies to be heated, but, on the contrary, the new heat is added to the reciprocating gases while they are going away from the bodies to be heated 30 and entering the piston chamber. The used gas coming from the bodies to be heated enters the piston chamber at the same time as the fresh hot gases from the source of 35 heat, and the two bodies of gases diffuse into each other and mix thoroughly while they are filling the piston chamber. At the moment of reversal of the direction of the piston the inflow of both gases ceases immediately. The mixed gases are then forced 40 out into the heating chamber and their temperature becomes even more uniform while they are thus expelled from the piston chamber into the heating chamber. Stratification 45 of heat is thereby entirely avoided.

50 It will be understood that the principles of my invention may be applied in many ways, and with the use of many forms of apparatus other than those herein specifically described. Therefore, no limitations 55 are to be imposed on my invention except such as are indicated in the appended claims.

I claim as my invention:

55 1. A method of heating that comprises establishing a reciprocating body of fluid, separating a portion of said fluid during each reciprocation thereof, adding heat to said separated portion, and then combining both portions prior to the next reciprocation.

60 2. A method of heating that comprises reciprocating hot gases through a system including a space to be heated, dividing said gases into two streams during each reciprocation thereof, passing one of said streams through the space to be heated, adding heat to the other stream and mixing

both streams together prior to the next reciprocation.

3. A method of maintaining the temperature of a body of hot gas while reciprocating said gas through a space to be heated, that 70 comprises simultaneously reciprocating a second body of gas, raising the temperature of said second body, and mixing the two bodies of gas during each reciprocation thereof. 75

4. A method of heating that comprises reciprocating a body of gas in contact with the object or space to be heated, reciprocating another body of gas through another path, raising the temperature of the said 80 second body while traversing said path, and mixing said bodies of gas together prior to the next reciprocation.

5. A method of heating that comprises reciprocating a body of gas in contact with 85 the object or space to be heated, causing a portion of said gas to traverse a by-pass communicating at its ends with a path of movement of said heating gas, and adding heat to the gas in said by-pass. 90

6. A method of heating that comprises establishing a reciprocating body of gases, adding fresh hot gases to said reciprocating body at a point of substantially neutral gas pressure, and removing waste gases from 95 said body at another point of substantially neutral gas pressure.

7. A method of heating that comprises reciprocating a body of gas in contact with the object or space to be heated, reciprocating another body of gas through a by-pass communicating at its ends with the path of movement of said first-named body of gas, adding hot gases to the gas in said by-pass 100 at a point where the pressure is neutral, and releasing waste gases from the system 105 at another point where the pressure is neutral.

8. A method of heating that comprises reciprocating a stream of gases in contact with the object or space to be heated, adding fresh hot gases to one side of the stream, allowing a corresponding volume of the surplus gases to spread from this side across the width of said stream, and finally removing the waste gases from the other side 110 of said stream. 115

9. A method of heating an elongated chamber or object that comprises reciprocating gases in contact with its full length, adding new hot gases to said reciprocating gases at one portion only of the length of said chamber or object, and removing waste gases from another portion of said gases. 120

10. A method of heating and guiding gases which are reciprocated in contact with the object or space to be heated, that comprises adding heat to a portion only of said reciprocated gases, allowing gases from 125 said heated portion to spread into another 130

- portion of said reciprocated gases, and removing waste gases from the latter portion of said reciprocated gases.
11. The method which comprises reciprocating a body of hot gases in contact with an object to be heated, and supplying new hot gases thereto from a single source of heat, alternately at opposite sides of said object, simultaneously with decrease of pressure at said points by reason of said reciprocation.
12. The method which comprises reciprocating a body of heating gases through a chamber by effecting variations in gas pressure, and introducing additional hot gases to said chamber at a point of relatively low pressure.
13. The method which comprises reciprocating a body of heating gases through a chamber by effecting variations in gas pressure at opposite sides of said chamber, and introducing additional hot gases to said chamber at points of relatively low pressure adjacent to said sides.
14. The combination with a chamber to be heated, of means for reciprocating heating gases through said chamber, and means for replenishing the gases with added hot gases from a single source of supply, alternately to each of opposite sides of said chamber during periods when said heating gases are moving toward the respective sides.
15. The combination with a furnace having a space to be heated, of means for reciprocating gases therethrough, centrally located means for adding hot gases to the reciprocated gases, and means for alternately feeding the added hot gases into the reciprocated gases at points where the last-named gases are under a reduced pressure.
16. In a furnace, a heating chamber, an auxiliary chamber adjacent the heating chamber, flues connecting the ends of the heating chamber with the ends of the auxiliary chamber, a combustion chamber having feeding channels for supplying hot gases into the connecting flues, and means in the auxiliary chamber for causing movement of gases back and forth through the heating chamber and for directing the supply of fresh hot gases into the moved gases as they emerge from the heating chamber.
17. In a furnace, a heating chamber adapted to receive heating gases, gas storage chambers for the gases at opposite sides thereof, flues connecting the heating chamber with the storage chambers, means communicating with both flues, for generating new hot gases, and means for simultaneously effecting reciprocation of the heating gases through the heating chamber and the influx of new hot gases into the heating gases when the last-named gases are passing through the connecting flues.
18. Heating apparatus comprising a main chamber adapted to receive heating gases, an auxiliary chamber, means for alternately increasing and decreasing the pressure in the auxiliary chamber, for effecting movement of the heating gases through the main chamber, and means for effecting an influx of new hot gases into the auxiliary chamber when decreased pressure exists therein.
19. Heating apparatus comprising an enclosure to be heated, means for reciprocating fluid through said enclosure, means for separating a portion of said fluid during each reciprocation thereof, means for adding heat to said separated portion, and means for thereafter combining said portions prior to the next reciprocation.
20. Heating apparatus comprising an enclosure to be heated, means for reciprocating gases through said enclosure, means for separating a portion of said gases during each reciprocation thereof, a burner adapted to add fresh hot gases to said separated portion, and means for thereafter combining both portions prior to the next reciprocation.
21. Heating apparatus comprising an enclosure to be heated, means for reciprocating gases through said enclosure, means for dividing said gases into two streams during each reciprocation thereof, means for directing one of said streams through the said enclosure, means for adding heat to the other stream, and means for thereafter mixing said streams prior to the next reciprocation.
22. Heating apparatus comprising an enclosure to be heated, means for reciprocating gases through said enclosure, a by-pass channel having its ends connected to the path of said reciprocating gases, and means for adding heat to the gases traversing said by-pass.
23. Heating apparatus comprising an enclosure to be heated, means for reciprocating gases through said enclosure, a by-pass channel of smaller capacity than the main path of said reciprocating gases and having its ends connected to said path, and means for introducing hot gases into said by-pass.
24. Heating apparatus comprising an enclosure to be heated, means for reciprocating gases through said enclosure, a by-pass channel of smaller capacity than the main path of said reciprocating gases and having its ends connected to said path, and means for introducing hot gases into said by-pass at a point of neutral gas-pressure therein.
25. Heating apparatus comprising an elongated enclosure to be heated, means for reciprocating gases transversely in contact with the full length of said enclosure, means for adding hot gases at one portion only of the length of said enclosure, and means for

removing waste gases from another portion of said enclosure.

26. Heating apparatus comprising an elongated enclosure to be heated, means for reciprocating gases transversely in contact with the full length of said enclosure, means for adding hot gases at one end only of said enclosure, and means for removing waste gases from the opposite end of said enclosure.

27. Heating apparatus comprising an enclosure to be heated, a piston for reciprocating gases through said enclosure, and a single source of heat arranged to supply equal amounts of heat to said reciprocating gases during each reciprocation thereof.

28. Heating apparatus comprising an elongated heating chamber, an elongated piston chamber, flues connecting said chambers at the sides thereof, by-pass channels having their ends opening into said flues, and means for adding heat to the gases traversing said by-pass channels.

29. Heating apparatus comprising an elongated heating chamber, an elongated piston chamber, flues connecting said chambers at the sides thereof, by-pass channels having their ends opening into said flues, a flue communicating with said by-pass channels, and a burner for introducing hot gases into said last-named flue.

30. Heating apparatus comprising an elongated heating chamber, an elongated piston chamber, flues connecting said chambers at the sides thereof, by-pass channels disposed at one part only of said heating chamber and having their ends opening into certain of said flues, and means for adding heat to the gases traversing said by-pass channels.

31. Heating apparatus comprising an elongated heating chamber, an elongated piston chamber, flues connecting said chambers at the sides thereof, by-pass channels disposed at one end only of said heating chamber and having their ends opening into certain of said flues, a flue extending transversely of said by-pass channels and communicating therewith through openings, and a burner for introducing hot gases into said last-named flue.

32. Heating apparatus comprising an elongated heating chamber, an elongated piston chamber, flues connecting said chambers at the sides thereof, by-pass channels disposed at one part only of said heating chamber and having their ends opening into certain of said flues, a flue extending transversely of said by-pass channels and communicating therewith through openings, a burner for introducing hot gases into said last-named flue, and means for adjusting the effective area of said openings.

33. Heating apparatus comprising an

elongated heating chamber, an elongated piston chamber, transverse partition means for dividing said piston chamber into sections, piston sections disposed in the sections of said piston chamber and adapted to oscillate on a common axis extending lengthwise of said chambers, flues connecting said chambers at the sides thereof, by-pass channels having their ends opening into certain of said flues, a flue communicating with said by-pass channels, and a burner for introducing hot gases into said last-named flue.

34. Heating apparatus comprising an elongated heating chamber, an elongated piston chamber, flues connecting said chambers at the sides thereof, by-pass channels disposed between said chambers and having their ends opening into said flues, a flue extending from one end of said enclosure and between said chambers, a burner for introducing hot gases into said last-named flue, and openings for connecting said last-named flue and said by-pass channels.

35. Heating apparatus comprising an elongated horizontal heating chamber, an elongated piston chamber adjacent to said heating chamber, flues connecting said chambers at the sides thereof, spaced by-pass channels having their ends opening into certain of said vertical flues, said by-pass channels being disposed at one end portion only of said heating chamber, a horizontal flue extending transversely to said by-pass channels, openings for connecting said horizontal flue and said by-pass channels, a burner at the outer end of said horizontal flue, and an outlet for waste gases at the end of said heating chamber opposite to said burner.

36. Heating apparatus comprising an elongated horizontal heating chamber, an elongated piston chamber adjacent to said heating chamber, vertical flues connecting said chambers at the sides thereof, transverse partition means for dividing said piston chamber into sections, piston sections disposed in the sections of said piston chamber and adapted to oscillate on a common horizontal axis extending lengthwise of said chambers, spaced by-pass channels having their ends opening into certain of said vertical flues, said by-pass channels being disposed between said chambers and at one end only of said heating chamber, a horizontal flue extending between said chambers and transversely to said by-pass channels, openings for connecting said horizontal flue and said by-pass channels, a burner at the outer end of said horizontal flue, and an outlet for waste gases at the end of said heating chamber opposite to said burner.

37. In heating apparatus, the combination with an oscillatory piston, of a cir-

cularly curved wall of refractory material beneath said piston and a circularly curved metal wall supporting said refractory wall.

38. In heating apparatus, the combination with an oscillatory piston, of a wall of refractory material curved circularly through an arc of less than 360° , means disposed at the opposite ends of said wall for securing the ends of said wall in position, and metal members connecting the said securing means, the said members surrounding the outer surface of said refractory wall and holding said wall in position.

39. In heating apparatus, the combination with an oscillatory piston, of a wall of refractory material curved circularly through an arc of less than 360° , means disposed at the opposite ends of said wall for securing the ends of said wall in position, and metal members connecting the said securing means, the said members surrounding the outer surface of said refractory wall and holding said wall in position, and structural means for positioning said securing means.

40. In heating apparatus, the combination of a heating chamber, a piston cham-

ber, a swinging piston in said piston chamber, a partition wall between said heating chamber and said piston chamber, a circularly curved wall beneath said piston chamber, a circularly curved plate for supporting said circularly curved wall, structural means for securing the ends of said partition wall in position, and structural means for uniting said plate and said structural securing means together.

41. In heating apparatus, the combination of a heating chamber, a piston chamber, a swinging piston in said piston chamber, a partition wall between said heating chamber and said piston chamber, a circularly curved wall beneath said piston chamber, a circularly curved plate for supporting said circularly curved wall, structural means for securing the ends of said partition wall in position, and structural means for uniting said plate and said structural securing means together, said last-named means being also adapted to support the weight of said chambers.

In testimony whereof I the said FRANZ PUENING have hereunto set my hand.

FRANZ PUENING.
